AUTOMATIC FEED FOR BOX MAKING MACHINES

Theodore L. Sargent, Berwyn, Ill.

Application February 15, 1950, Serial No. 144,291

5 Claims. (Cl. 93—54)

This invention relates to improvements in box making machinery. More particularly, it has to do with improvements in automatic mechanism for feeding a box and a wrapper to a folding machine where the wrapper is folded around the box.

In the process of making certain types of cardboard boxes as, for example, the flat boxes in which candies are sold, a cardboard shell is first formed and then a decorative outer wrapper is secured thereover.

At present this wrapper is applied in the following manner. An operator sits alongside a conveyor belt facing the belt and facing a folding machine which is disposed adjacent the opposite side of the belt. A supply of cardboard box shells are stacked near the operator. A feeding and gluing machine places wrappers on the conveyor belt at a point remote from the operator's station with their finished sides faced downward and their unfinished, upturned sides coated with glue. The conveyor belt is periodically indexed to move the wrappers consecutively toward the operator's station.

When a wrapper is stopped in front of the operator he centers a cardboard shell on the wrapper and then, reaching across the belt, positions the wrapper and the shell under a forming plunger of the folding machine. As the plunger descends, it takes the box out of the hands of the operator and continues downwardly in the folding operation.

This procedure has several disadvantages. First, the positioning of the shell and wrapper under the plunger is dependent upon the skill of the operator. If the shell is not positioned accurately, the box is liable to be crumpled or broken along the sides. Secondly, the operator must repeatedly place his hands under the moving plunger of the folding machine, thus running the risk of having his hands caught in the mechanism. It will be readily appreciated that a tired operator would not only spoil a large quantity of boxes but would be in constant danger of being injured.

It is therefore an important object of this invention to provide a device for automatically and mechanically feeding box shells and wrappers to a folding machine.

Another object of this invention is to provide a feeding device that does not require the services of a skilled operator.

A further object of this invention is the provision of a feeding device that is simple in design and efficient in operation.

A still further object of this invention is to provide a feeding device which may be used with any standard gluing and folding equipment now on the market.

According to the features of the present invention the operator's station is now located alongside the conveyor belt but at a distance away from the folding machine equal to the distance the belt will travel when it is indexed twice. At this station, identified as station No. 1, the only duty of the operator, who may be an unskilled worker, is to center the box shell on the glued wrapper. The wrappers are larger than the shells and have a cen-

2

tral portion underlying the shell and four side flaps which are arranged to be folded up along the sides of the shell and then down into the shell along the inner walls thereof.

When the conveyor belt is indexed, the shell and the wrapper are moved to station No. 2 where a horizontal fluid power cylinder is mounted laterally of the conveyor belt. The plunger of the cylinder overlies the belt and carries a pusher plate which contacts the shell and the wrapper and moves them laterally across the belt to a position where one flap overhangs the edge of the belt. The plunger of a second, vertically acting fluid cylinder moves upwardly alongside the conveyor belt and contacts the overhanging flap to wipe it up against the side of the box shell. The two plungers are then retracted and the conveyor belt is indexed to move the shell and the wrapper to station No. 3.

At station No. 3, a fluid cylinder is mounted adjacent the conveyor belt at the position formerly occupied by the operator. The cylinder has a rod extending over the conveyor belt which is equipped with a pusher plate for contacting the shell and urging it and the wrapper laterally off the belt and under the plunger of the folding machine. It will be recognized that the one flap is folded up at station No. 2 so that it will not be crumpled or twisted as the box is pushed laterally at station No. 3.

Thus, according to the present invention, at consecutive stations the shell is centered on a glued wrapper, the shell and the wrapper are moved laterally to a point where one flap is folded up against the side of the shell, and finally the shell and wrapper are positioned under the plunger of the folding machine.

Other and further features, objects and advantages of the present invention will be apparent to one skilled in the art from the following detailed description taken in connection with the accompanying drawings.

On the drawings:

Figure 1 is a top plan view of a feeding device constructed according to the teachings of the present invention and shown as mounted on a standard gluing and folding machine;

Figure 2 is a side elevational view of the machine of Figure 1;

Figure 3 is a vertical sectional view taken on line III—III of Figure 2 showing the shell positioned on the glued wrapper;

Figure 4 is a vertical sectional view similar to Figure 3 but showing one flap of the wrapper folded against one side face of the shell, which operation takes place at station No. 2;

Figure 5 is a vertical sectional view similar to Figures 3 and 4 and showing the box in its finally wrapped condition;

Figure 6 is a fragmentary vertical sectional view taken on line VI—VI of Figure 1;

Figure 7 is a fragmentary vertical sectional view, similar to Figure 6, illustrating an advanced stage of the operation;

Figure 8 is a fragmentary vertical sectional view taken on line VIII—VIII of Figure 1; and

Figure 9 is a schematic diagram of the control circuit used with the mechanism of the invention.

As shown on the drawings:

In Figures 1 and 2, the reference numeral 10 indicates a conveyor belt that is disposed at either end around rollers 12 and 13. The roller 12 is rotatably mounted on a gluing and belt indexing machine 15, while the roller 13 is journaled in bearings on a platform 17 of a folding machine 19.

The gluing machine 15 forms no part of this invention since it is a standard machine used to put glue on the wrappers and deposit the wrappers on the conveyor belt consecutively. This machine is equipped with a one-

revolution clutch which, when energized through a switch, generally indicated by the reference numeral 20, advances the conveyor belt a predetermined distance. The machine 15 also has a rotating shaft 22 which is coordinated with the movements of the conveyor belt and which carries an arm 23. The arm 23 is arranged to trip a switch 24 during its rotation for a purpose to be explained hereinafter.

The folding machine 19 includes an upright support structure 26 on which is secured the table 17 by means of bolts 27 through a flange portion of the table. A vertical shaft 29 is journaled in the upright support structure 26 and is driven through bevel gears 28 from an electric motor 29a. At the upper end of the shaft 29 a cylindrical cam 30 is keyed thereon having a cam slot 31 in which a roller follower 32 is disposed. An arm 35 is pivotally attached to a sliding bar 36 at one end and at the other end pivotally carries the roller follower 32. The bar 36 is slidably guided in ways 37 which are supported by means of a connecting arm 39 from the main support structure 26. At its lower end the bar 36 carries a plunger 40 which is of a size to fit inside the box shell as it descends. This folding machine 19 is not a part of this invention, and the operation of the folding machine after it contacts the box shell and starts the folding operation will not be described in detail. In general, the plunger 40 moves downwardly into the box shell and presses the box into an aperture 42 in a second table surface 43 extending laterally from the upright support structure 26. As the plunger continues its downward movement, the flaps of the wrapper are folded over the edges of the shell and down along the inner side walls thereof. The plunger then moves back up to release the box at the surface of the table 43 from which position it is removed by the contact of the next box being positioned under the plunger.

Referring to Figure 1, it will be seen that at station No. 1, where the operator stands, the box B, which has side flaps W1, W2, W3 and W4, is centered on the wrapper. Since in a later operation the box and the wrapper must be moved laterally across the conveyor onto the folding machine and into abutting contact with the box which has previously been wrapped, it is necessary that one side flap W1 be folded up against the adjacent edge of the plate before this lateral movement takes place. This first folding operation is performed at station No. 2 defined by the superstructure 44 (Figure 1). This superstructure straddles the conveyor belt, as shown in Figure 6, and includes upright corner post members 44a, lateral angle members 45 secured across the top of the posts 44a, and longitudinal bars 46 also secured thereacross.

The superstructure 44 supports a laterally extending fluid cylinder 47 secured to a base 48 which is adjustably mounted on an angle bracket 50 by means of bolts 51 which extend through slots 50a in the upper surface of the angle bracket 50. The bracket 50 is also secured to the superstructure 44 by bolts 52.

The power cylinder 47 may be of any standard construction, being of a double-acting type having fluid inlet connections 53 and 54 and a piston rod 56 which extends from each end of the cylinder through suitable packing glands. An adjustable clamp 58 on one end of the piston rod regulates the throw of the piston, while the other end of the piston rod 56 carries a plate 59 that extends longitudinally of the conveyor across the superstructure for support at either end by rollers 61 which are mounted on a rod 62 secured to the plate 59 and which travel on the horizontal ledges of the angle members 45.

A secondary pusher plate 63 is secured to the bottom portion of the pusher plate 59 and is arranged to contact one side edge of the box B, as seen in Figure 6, and, as the piston rod 56 moves to the left, it will move the box laterally of the conveyor belt to a point abutting a pivoting arcuate stop member 64 with the flap W1 over-

hanging the edge of the conveyor belt. An air supply pipe 66 suitably mounted beneath the conveyor belt has a plurality of orifices which will direct air upwardly to the left to engage the flap W1 and prevent it from drooping down. The air jets therefore will hold the flap W1 in a substantially horizontal position. It will be understood, of course, that the pipe 66 will be connected to a suitable source of air under pressure.

The pusher plate 59 also carries a contact rod 68 which is adjustably threaded into the plate 59 and locked therein by lock nuts 69 and 69a. As the piston rod 56 of the power cylinder 47 moves to the left, the contact rod 68 will contact a plunger 71 of an electric switch 72, as shown in Figure 7, which will energize a solenoid controlled valve for directing air to the lower end of a double-acting fluid cylinder 75 which is mounted by means of a bracket 76 from the superstructure 44. The piston rod 78 of the cylinder 75 carries at its upper end a head 79 which extends a considerable distance longitudinally of the conveyor belt and carries a rubber wiper 81 in a slot 82 of the head. As seen in Figure 7, as the head 79 moves upwardly, the wiper 81 wipes the flap W1 up against the side edge of the box B. An adjustable clamp 77 is secured to the lower end of the piston rod 78 to limit the upward movement of the rod.

The head 79 carries an upstanding peg 85 which, when the piston rod 78 is at the upper end of its stroke, contacts a plunger 86 of an electric switch 87 which energizes the solenoid controlled valve that directs air to the inlet 53 of the fluid cylinder 47 to retract the piston rod 56 and the pusher plate 59.

The head 79 also carries an upstanding arm 89 which normally rests against an outstanding arm 90 which is rigidly secured to a shaft 91 on which the pivoting stop member 64 is also keyed. As the head 79 moves upwardly, the arm will be actuated, as shown in Figure 7, and the pivoting stop will be pivoted away from the box B and out of the path of the oncoming wiper 81. A bar 93 is adjustably secured between the angle members 45 by means of set screws 94 threaded into slots 95 in the bar 93. The function of the bar 93 is to lie close against the top of the box B, as shown in Figure 7, and prevent it from being raised off the conveyor belt as the wiper 81 moves the flap W1 up against the side of the box.

As the plunger 56 of the cylinder 47 is retracted due to the tripping of the switch 87 by the peg 85 on the head 79 of the plunger 75, the contact between the arm 68 and the plunger 71 of the switch 72 is broken and the solenoid valve controlled by the switch 72 is de-energized and the piston rod 78 is moved downwardly by a spring mounted inside of the power cylinder 75.

From the foregoing description, it will be seen that at Station No. 2 the box and the wrapper are first slid to the edge of the conveyor belt where the side flap W1 is wiped up against the side of the box B. The stop 64 prevents the box from being moved too far off the conveyor while the bar 93 prevents lifting of the box as the flap W1 is wiped up.

The box with the wrapper secured to the bottom surface thereof and with the one flap W1 moved onto the side edge is moved along to Station No. 3 as the conveyor belt is indexed. At this station the leading flap W2 slides under an adjustable stop arm 98 which is mounted in a block 99 (Figure 8) and secured therein by means of a set screw 100. As the side of the box B abuts this stop 98 a jet of air is directed downwardly into the box by means of a nozzle 102 suitably supported at this point and connected to a source of air under pressure. The air jet moves downwardly and diagonally into the box and pushes the box firmly against the stop 98 and rearwardly against a pair of suction cups 104 which are mounted on a pusher plate 105 (Figure 8) secured to the front end of a piston rod 106 extending from a power cylinder 107. The suction cups 104

are connected by a line 109 to a source of vacuum pressure.

It is the function of the pusher plate 105 to move the box with its wrapper laterally off the conveyor belt onto the platform 43 of the folding machine and over to the position generally indicated by the aperture 42 (Figure 1). This is a rather long movement and one which requires a very long piston rod 106. It is therefore necessary that a carrier rod 110 be provided for this piston rod 106.

The cylinder 107 is provided with air inlets 112 and 113 and is mounted on a plate 115 which is adjustably mounted by bolts 114 in slots 116a of ways 116 which are rigidly mounted on a support structure 118. The support structure 118 may suitably include upright legs 118a and cross braces 118b.

To support the carrier rod 110 there is provided up-standing arms 120 which are rigidly secured to the end of the cylinder 107 for support thereby. The rod 110 is rigidly secured in the support members 120. Support arms 122 are rigidly attached to the end of the piston rod 106 and are provided with apertures 124 in their upper portion through which the carrier rod may freely pass. A compression spring 125 is disposed around the carrier rod 110 between each support arm 120 and the associated arm 123.

In the position indicated in Figure 8 the piston rod 106 has been retracted to the right so that the support bracket at the right-hand end of the piston rod is supporting that end from the carrier rod 110. It will be understood that when the piston rod 106 is moved to the left to move the box B onto the folding machine, the opposite end of the piston rod will be supported.

At the proper point in the sequence of operations the piston rod 106 is moved out of the cylinder 107 to the left, pushing the box B onto the folding machine over the aperture 42 thereon. If a box has previously been wrapped, it will be moved off the platform 43 by the next box which is being positioned thereon. It is to be noted that the box B is still being held by the suction cups 104 and these cups will continue to hold it until the plunger of the folding machine takes the box away therefrom in the folding operation. At this point the plunger 106 will be retracted.

Thus, at station No. 3 the box is first positioned against the adjustable stop 98 and the suction cups 104. The piston rod 106 is then actuated to move the box onto the platform 43 of the folding machine to thereby position it in place under the plunger.

From the foregoing description it will be seen that there is provided in this invention a simple, positively acting feeding mechanism which will automatically take the box after it has been centered on the wrapper, fold up one edge of the box so that that edge will not be wrinkled in subsequent operation, and then move the box into position under the plunger of the folding machine. With this apparatus the positioning of the box under the plunger of the folding machine is absolutely positive and accurate and there is no possibility of the box being spoiled due to inaccuracy of aligning. Further, the operator is completely relieved of the danger of getting his hand caught in the plunger of the folding machine.

It is a particular feature of this invention that all of the various apparatus of this feeding device is adjustable for various sizes of boxes. It is contemplated that this machine will be arranged to accommodate boxes in the range of from a box three inches in length, two and one-quarter inches in width, and one inch in height to a box twenty-one inches in length, thirteen inches in width, and four and one-quarter inches in height. To this end the various power cylinders are adjustably mounted on their support structure, the hold-down bar 93 is adjustable vertically, the throw of the piston rod of the various cyl-

inders may be adjusted, and the stop bar 98 may be adjusted.

It will be understood, of course, that the drive mechanism of the gluing machine 15 is such that for each revolution of the shaft 22 the conveyor belt will be indexed a distance equal to the distance between the stations Nos. 1, 2 and 3. It is further to be noted that the arm 23 is so positioned on the rod 22 as to contact the plunger of the switch 24 just at the end of the indexing movement.

It is contemplated in this invention that the starting of each indexing stroke of the conveyor belt 10 will be timed with the downward movement of the plunger 40. This is accomplished by means of a cable 130 which is attached at one end to the switch 20 and at the other end a depending ear 131a of a table 131 which is slidably mounted in a slot 132 in a housing 133. The housing 133 may be secured to a member of the support structure 26 adjacent a cam 134 which is keyed to the shaft 29. As the cam 134 rotates with the shaft 29 it will contact the table 131 and slide it into the slot 132 against the resistance of a spring 135 disposed in the housing 133. Thus the switch 20 will be periodically tripped.

The cam 134 may be designed so that the switch 20 is tripped when the plunger 40 is at or near the bottom of its downward travel.

In Figure 9 is shown a schematic view of a control circuit for the feeding device of this invention. In this view it is seen that the fluid cylinder 47 is provided with a solenoid controlled valve 140. In this diagrammatic showing the solenoids 141 and 142 are connected to a rod inside the valve 140 which controls the shifting of the air valve. The valve 140 may suitably have two vent connections 145 and 146, two air outlet connections 147 and 148, and an air inlet connection 149. Flexible tubes 150 and 151 connect the valve to the cylinder 47.

Similarly, the passage of air through the cylinder 75 is controlled by a valve 152 controlled by a solenoid 153. The valve housing has an air inlet connection 155, air vents 156 and 157, and air outlets to the cylinders 158 and 159.

The cylinder 107 is controlled by an air valve 151 which in turn is controlled by a solenoid 162. Air lines 163 and 164 connect the cylinder 107 to the air valve 161. The valve housing has bent ports 165 and 166 and an air inlet connection 167.

Assume to start the cycle of operations that the one revolution clutch of the machine 15 has just been actuated and the arm 23 is moving through its rotation. Just at the end of the movement of the conveyor belt the switch 24 is tripped by the arm 23, thus energizing the solenoid 142 from a source of power 170 through the conductor 171, the conductor 172, the switch 24, the conductor 173, the winding of the solenoid 142, the conductor 174, the conductor 175 to the other side of the line 176.

When the solenoid 142 is energized, the plunger will be moved in the valve 140 to admit air to the line 151 which directs air to one side of the cylinder 47, thus causing the piston rod 56 to be moved across the conveyor belt 10. The pusher plate 59 moves the box to the edge of the conveyor belt 10 so that the overhanging flap may be wiped upwardly by the head 79 of the cylinder 75. Just as the box abuts the pivoting stop 64, the rod 68 contacts the plunger 71 of the switch 72 to close this normally open switch and thus energize the solenoid 153 from the source of power 170 through the conductor 178, windings of the solenoid 153, the conductor 179, the switch 72, the conductor 180, and the conductor 175 to the other side of the line. When the solenoid is energized, the valve 152 will be adjusted to direct air to the left-hand side of the cylinder 75, as shown in Figure 9. As the head 79 of the cylinder 75 moves upwardly, it wipes the flap W2 of the wrapper against the side of the box, and, just at the end of the wiping stroke, the peg 85

on the head 79 contacts the plunger 86 of the normally open switch 87 to close the switch and thus energize the solenoid 141 which controls the valve 140. The solenoid 141 is energized from the power source 170 through the conductor 182, the switch 87, the windings of the solenoid 141, the conductor 183, and the conductor 175 to the other side of the line.

It will be understood, of course, that the arms 23 only momentarily close the switch 24 and momentarily energize the solenoid 142. Since the solenoid 142 is not energized when the switch 87 is closed, the solenoid 141 can shift the valve 140 in an opposite direction to direct air to the top end of the cylinder 47 and thus retract the pusher plate 59 and permit the switch 72 to automatically open. When the switch 72 opens, the solenoid 153 will be deenergized and a spring in the cylinder 75 will move it to its lower retracted position.

The operation of the cylinders 47 and 75 takes place between the periods at which the conveyor belt is indexed and while the conveyor belt is motionless. After these operations are complete, the conveyor belt will be indexed in response to the downward movement of the plunger 40, and the box will be moved to Station 3 in front of the pusher plate 105.

The valve 161 is actuated by the solenoid 162 to direct air to the lower end of the cylinder through the line 165 when a cam 190 (Figures 1 and 2) keyed to the lower end of the shaft 29 actuates a normally open switch. The cam 190 is so designed that it will hold the switch 191 closed during about one-third of its rotation. During the time the switch is closed, the solenoid 162 will be energized and air will be directed through the line 165 to one end of the cylinder 187, and the pusher plate 195 will be actuated to move the box into position under the plunger 140 of the folding machine.

The solenoid 162 is energized from the power source 170 through the conductor 193, the windings of the solenoid 162, the conductor 194, the switch 191, the conductor 195, and the conductor 175 to the other side of the line.

The box will be held in this position until the ram moves downwardly and takes it from the suction cups 104. Soon thereafter the cam permits the switch to open and deenergize the solenoid 162, whereby a spring in the valve 161 will shift the valve member and direct air to the opposite end of the cylinder 187 to return the pusher plate 105 to its initial position.

In summary, the movement of the conveyor belt is controlled by the downward movement of the plunger. The actuation of the pusher plate 59 of the cylinder 47 is controlled by the switch 24 which is actuated by the lever 23 connected to the gluing machine 15. The solenoid 153 of the cylinder 75 is energized by the forward movement of the pusher plate 59 and is deenergized by the backward movement of that plate. Also, the upward movement of the pusher plate 79 of the cylinder 75 retracts the pusher plate 59 to its initial position.

From the foregoing description it will be seen that there is provided in this invention a novel efficient feeding mechanism which is adaptable for use with standard gluing and conveying equipment and is simple in construction and operation. This feeding mechanism substantially eliminates the possibility of injuries to the operator and spoilage of the boxes. Further, this equipment will greatly increase production due to this decrease in spoilage and also due to the fact that the operator has only one duty to perform. This simple job of sliding the cardboard shell on the wrapper does not require a skilled operator. The adaptation of air power and solenoid valve control to the feeding mechanism not only provides low initial cost of the equipment but also reduces maintenance cost due to its simplicity of operation.

It will be understood that modifications and variations may be effected without departing from the scope of the novel concepts of the present invention.

I claim as my invention:

1. A device for moving an article along a support surface, said article having a wrapper secured to the bottom wall thereof and having flaps extending beyond the marginal edges of the article, comprising a support structure straddling said support surface, a first power cylinder mounted on said structure and having a piston rod reciprocable laterally above said support surface to contact an article thereon and move it across the support surface, a pivotal stop member limiting the movement of said article to position the article at the edge of the support surface with one wrapper flap extending thereover, a second power cylinder mounted vertically alongside the edge of said first support surface and having a piston rod arranged to fold said overhanging flap against the side of the article, a control unit for said second power cylinder mounted on said structure, means on the piston rod of said first power cylinder for actuating said control unit to energize said second power cylinder, a switch on said structure controlling the retraction of said first piston rod, and means on the piston rod of said second power cylinder to trip said switch, effecting retraction of said second piston rod.

2. In a box making machine or the like having a surface for supporting an article having a wrapper secured to the bottom wall thereof and having flaps extending beyond the marginal edges of the article, means reciprocable laterally of the surface for pushing the article laterally to a position at one side of the surface with a flap overhanging the edge of the surface, means reciprocable vertically for folding the overhanging flap against one side of the article, and means actuated by said laterally reciprocable means when the box is moved to said position for initiating upward movement of said vertically reciprocable means.

3. In a box making machine or the like having a surface for supporting an article having a wrapper secured to the bottom wall thereof and having flaps extending beyond the marginal edges of the article, means reciprocable laterally of the surface for pushing the article laterally to a position at one side of the surface with a flap overhanging the edge of the surface, means reciprocable vertically for folding the overhanging flap against one side of the article, and switch means actuated by said laterally reciprocable means when the box is moved to said position for initiating upward movement of said vertically reciprocable means.

4. In a box making machine or the like having a surface for supporting an article having a wrapper secured to the bottom wall thereof and having flaps extending beyond the marginal edges of the article, means reciprocable laterally of the surface for pushing the article laterally to a position at one side of the surface with a flap overhanging the edge of the surface, means reciprocable vertically for folding the overhanging flap against one side of the article, means actuated by said laterally reciprocable means when the box is moved to said position for initiating upward movement of said vertically reciprocable means, and means actuated by said vertically reciprocable means at the limit of its upward movement for initiating return movement of said laterally reciprocable means.

5. In a box making machine or the like having a surface for supporting an article having a wrapper secured to the bottom wall thereof and having flaps extending beyond the marginal edges of the article, means reciprocable laterally of the surface for pushing the article laterally to a position at one side of the surface with a flap overhanging the edge of the surface, means reciprocable vertically for folding the overhanging flap against one side of the article, switch means actuated by said laterally reciprocable means when the box is moved to said position for initiating upward movement of said vertically reciprocable means, and switch means actuated by said vertically reciprocable means at the limit of its upward movement for

initiating return movement of said laterally reciprocable means.
